US00D849499S

(12) **United States Design Patent** (10) **Patent No.:** **US D849,499 S**
(45) **Date of Patent:** **** May 28, 2019**

(54) **MULTI-TOOL FOR USE ON INSTRUMENTS**

(71) Applicant: **Music Nomad, LLC**, Sonoma, CA (US)

(72) Inventors: **Rand Rognlien**, Sonoma, CA (US); **Pieter Schouten**, Berkley, CA (US)

(73) Assignee: **Music Nomad, LLC**, Sonoma, CA (US)

(**) Term: **15 Years**

(21) Appl. No.: **29/582,254**

(22) Filed: **Oct. 26, 2016**

(51) **LOC (11) Cl.** **08-05**

(52) **U.S. Cl.**

USPC **D8/105**

(58) **Field of Classification Search**

(57) **CLAIM**

The ornamental design for a multi-tool for use on instruments, as shown and described.

DESCRIPTION

FIG. 1 is a perspective view of the multi-tool for use on instruments, showing our new design;

FIG. 2 is a top plan view thereof;

FIG. 3 is a bottom plan view thereof;

FIG. 4 is a first side elevation view thereof;

FIG. 5 is a second side elevation view thereof;

FIG. 6 is front elevation view thereof; and,

FIG. 7 is a rear elevation view thereof.

(Continued)

The broken lines are shown for the purpose of illustrating parts of the article that form no part of the claimed design.

1 Claim, 4 Drawing Sheets
